UNITED STATES PATENT OFFICE.

ALBERT E. PALMER, OF SAN DIEGO, CALIFORNIA.

MUCILAGE DISTRIBUTOR.

Application filed January 31, 1927. Serial No. 164,738.

My invention relates to a device for distributing mucilage on paper, and the like.

The objects of my invention are: first, to provide a device of this class whereby mucilage may be uniformly distributed and spread over a surface such as paper, or other surface, for adhesively securing the same to another surface; second, to provide a device of this class for uniformly distributing mucilage in any desired reasonable amount over a surface; third, to provide a device of this class whereby the discharge of mucilage from the device may be variously controlled independently of the pressure applied by the device on the surface over which the mucilage is to be spread; fourth, to provide a mucilage containing and distributing receptacle having valve means therein for simultaneously controlling the discharge opening for the mucilage and the admittance of air therein, which valve means, when released, automatically covers the mucilage discharge opening and the opening for admitting air, thus providing a device which is closed or sealed at all times except when in use; fifth, to provide a device of this class in which pressure may be created by an adjustable section or cover to facilitate the discharge of mucilage from the receptacle; sixth, to provide, as a whole, a novelly constructed mucilage distributing device; and, seventh, to provide a device of this class which is particularly simple and economical of construction, durable, efficient, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which form a part of this application in which:

Figure 1 is a side elevational view of my mucilage distributor, showing the same in normal position for distributing and spreading mucilage over a surface; Fig. 2 is a longitudinal sectional view thereof taken

through 2-2 of Fig. 3, showing certain parts and portions in elevation to facilitate the illustration; Fig. 3 is a longitudinal sectional view thereof taken through 3-3 of Fig. 2, showing certain parts and portions in plan to facilitate the illustration; Fig. 4 is a front end elevational view thereof; and, Fig. 5 is a transverse sectional view thereof taken through 5-5 of Fig. 2.

Like characters of reference refer to similar parts and portions throughout the several views of the drawings.

The receptacle 1, cover 2, valve member 3, pivot member 4, button 5, and the spring 6 constitute the principal parts and portions of my mucilage distributor.

The receptacle 1 is relatively long and preferably cylindrical, and is reduced at one end in smooth curved lines. The normally under side of the reduced end is provided with a flat surface 1^a extending angularly with the longitudinal extent of the receptacle and adapted for engaging the surface over which mucilage is to be spread. Near the normally forward end of the flat portion 1^a, is provided a long transverse opening 1^b which is provided at the inside of the receptacle with a valve seat 1^c which is adapted to be engaged by an elongated valve portion 3^a secured to the normally forward end and extended transversely to the longitudinal extent of the valve member 3 positioned within the receptacle.

The end of the receptacle 1, opposite the reduced end thereof, is open and is externally threaded. Over this end is mounted a removable cap or cover 2 which may be removed for filling the receptacle with mucilage and which may be adjusted axially for varying the pressure within the receptacle when desired.

The valve member 3 is in the form of a long lever positioned longitudinally within the receptacle and pivotally mounted intermediate its ends on a pivot member or pin 4 extending transversely through the receptacle. The valve member 3 is loosely mounted on said pivot pin and is located thereon by a transverse groove 3^b at the under side of the valve member, as shown in Figs. 2 and 3. The valve portion 3^a of the valve

member is normally retained against its seat by a compression spring 6 positioned within the receptacle and between the upper side of the forward portion of the valve member 5 and the inner wall of the receptacle. The spring 6 is located on the valve member by a lug 3° bent upwardly from the valve member, as shown in Figs. 2 and 5.

The opposite or normally rear end of the 10 valve member is provided with a reduced upwardly turned portion 3^a having a valve portion 3^e which terminates at its upper end in a reduced stem 3^f which extends through the wall of the receptacle at the upper side 15 and near the rear end thereof. To the upper or outer end of the stem 3^f is screwably secured a button 5 for operating the valve member. Surrounding the opening in the receptacle 1 through which the stem 20 3^f extends is a valve seat 1^d engageable by the valve portion 3^e. The opening, through which the stem 3^f extends, is slightly elongated, as indicated by 1^e in Fig. 2, to permit longitudinal movement of the stem 3^f relative to the longitudinal extent of the receptacle when the button 5 is depressed.

From the above it will be seen that, when the button 5 is depressed, the mucilage discharge opening at the forward end of the receptacle, as well as the air inlet opening at the rear end of the receptacle, will be uncovered permitting mucilage to flow freely out of the forward end, and when the device 25 is drawn over a surface with the flat side 1^a thereagainst, the mucilage will be uniformly distributed over the surface. The amount of mucilage discharged is controlled by the distance the button 5 is depressed. Should the mucilage become clogged at the discharge opening, the cover 2 may be screwed outwardly with the valves open and then inwardly after the valves have been again closed.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In a device of the class described, a receptacle having a discharge opening in the side wall at one end and an air inlet opening in the upper side wall at its opposite end, a valve lever positioned within said receptacle and pivotally mounted intermediate its ends therein, said lever having a valve portion at one end adapted to cover the discharge opening at one end of the receptacle and provided at its other end with

another valve portion adapted to cover said air inlet opening, and means for controlling said valve lever.

2. In a device of the class described, a receptacle having a discharge opening in the side wall at one end and an air inlet opening in the upper side wall at its opposite end, a valve lever positioned within said receptacle and pivotally mounted intermediate its ends therein, said lever having a valve portion at one end adapted to cover the discharge opening at one end of the receptacle and provided at its other end with another valve portion adapted to cover said air inlet opening, spring means for normally forcing said valve portions over said openings, and a valve control button secured to the valve portion adapted to cover said air inlet opening.

3. In a device of the class described, a substantially cylindrically shaped receptacle having an obliquely inclined flattened surface extending over one end portion, a discharge opening in said flattened surface at one end of the receptacle, an air inlet valve opening in the side surface at the opposite end of said receptacle, the seating of said air inlet valve facing inwardly of the receptacle and valve means within the receptacle for closing said openings, said means being operable from the exterior of the receptacle.

4. In a device of the class described, a substantially cylindrically shaped receptacle having an obliquely inclined, flattened surface over one end portion, a discharge opening in said flattened surface at the end of the receptacle, an air inlet opening in the side surface at the opposite end of said receptacle, a pivot member secured intermediate the said openings extending transversely through the receptacle, a lever positioned longitudinally within the receptacle and pivotally supported on said pivot means, valve means at either end of said lever for closing said openings from within the receptacle, means for resiliently forcing said valve means into closed position and means operable from without said air inlet opening for simultaneously uncovering said openings.

5. In a device of the class described, a receptacle having a discharge opening in the lower side wall at one end and an air inlet opening in the upper side at its opposite end, a valve lever positioned within said receptacle and pivotally mounted intermediate its ends therein, said valve lever having a valve portion on each opposite end adapted to cover and uncover both of said openings simultaneously with the movement of said lever on its pivotal mounting.

6. In a device of the class described, a receptacle having a discharge opening in the lower side wall at one end and an air inlet opening in the upper side at its oppo-

site end, a valve lever positioned within said receptacle and pivotally mounted intermediate its ends therein, said valve lever having a valve portion on each opposite end adapted to cover and uncover both of said openings simultaneously with the movement of said lever on its pivotal mounting, and

spring means within said receptacle tending to hold said valves normally in closed engagement with said openings.

In testimony whereof, I have hereunto set my hand at San Diego, California, this 19th day of January, 1927.

ALBERT E. PALMER.
